UNITED STATES PATENT OFFICE.

CHARLES T. STUART, OF BROOKLYN, NEW YORK.

THILL-COUPING.

SPECIFICATION forming part of Letters Patent No. 307,350, dated October 28, 1884.

Application filed March 1, 1884. (No model.)

To all whom it may concern:

Be it known that I, CHARLES T. STUART, of Brooklyn, Kings county, State of New York, have invented a new and useful Improvement 5 in Thill-Couplings, of which the following is a specification, reference being had to the accompanying drawings, forming part of the same, in which—

Figure 1 is a side elevation of a thill-coupling embodying my invention. Fig. 2 is a top view of the same and a portion of an axle on which the coupling is secured. Fig. 3 is a section on line *y y*, Fig. 2; and Fig. 4 is a central vertical section of a part of an axle and the 15 said coupling.

My invention relates to a thill-coupling formed of two clips on the axle, between which the eye of the thill-iron is held by a pin passing through the eye; and it consists 20 in the devices hereinafter described and claimed.

A and A' represent two clips secured upon the bolster B and axle C of a vehicle by straps D D' and nuts *a a'* in the usual way. On the 25 front leg of each clip is formed a lug or jaw, *b b'*, between which jaws the loop or hook E of the thill-iron is held by a pin, *c*. The jaw *b'* is provided with the said pin *c*, which pro-

jects from its side toward the opposite jaw, the free end of the pin passing through a hole in the latter. The said pin is welded solid to the said jaw *b'* so that when it is passed through the eye of the thill-iron and the hole in the opposite jaw the thill-iron cannot be detached from the pin except by loosening the 30 clip A and sliding it on the axle, thereby uncovering the free end of the pin *c*. The clips are prevented from displacement on the bolster and axle by a strap or plate, *d*, let into the bolster under the clips and having its 35 ends turned up, as seen in Fig. 4.

What I claim as my invention, and desire to secure by Letters Patent, is—

The described thill-coupling consisting of the clip A', provided with a jaw, *b'*, and pin 45 *c*, solidly connected thereto, the clip A, provided with a jaw, *b*, with a hole to receive the end of the pin *c*, and a thill-iron provided 50 with an eye or hook, *E*, through which passes the said pin, all constructed and combined as 55 and for the purpose described.

CHARLES T. STUART.

In presence of—

ROBERT JACKSON,
A. G. N. VERMILYEA.
